UNITED STATES PATENT OFFICE.

WILLIAM C. BUHLES, OF SAN FRANCISCO, CALIFORNIA, ASSIGNOR TO
JULIUS A. LANDSBERGER, OF ALAMEDA, CALIFORNIA.

CLOSURE FOR RECEPTACLES.

SPECIFICATION forming part of Letters Patent No. 783,608, dated February 28, 1905.

Application filed April 4, 1904. Serial No. 201,571.

To all whom it may concern:

Be it known that I, WILLIAM C. BUHLES, a citizen of the United States, residing at San Francisco, in the county of San Francisco and State of California, have invented certain new and useful Improvements in Closures for Receptacles, of which the following is a specification.

My invention relates to closures for receptacles, and more particularly to the class in which the cover is held in place by atmospheric pressure without the aid of any mechanical fastening.

The object of my invention is to make a tight and secure closure without the aid of any mechanical fastening device by causing the sealing-gasket to perform the double function of forming an air-tight packing for the joint between the receptacle and its cover and also a complete or auxiliary means for holding the said cover in place. It is especially, although not exclusively, adapted to receptacles having small mouths, where the area of the cover may not be sufficient to make an atmospheric-pressure seal reliable. When using a small cap or cover, the pressure of the atmosphere on the limited area may not be sufficient to hold it securely in place.

An embodiment of my invention is shown in the accompanying drawings, which represent the application of my invention to a glass receptacle, such as a bottle or jar, and to a sheet-metal cover for the same.

Figure 1 is a vertical section of the upper part of such receptacle and its cover with an intermediate composition or gasket clamped in position previous to the application of heat. Fig. 2 is a similar view with the closure completed after the application of heat and pressure. Fig. 3 is a section of one of the covers associated with a gasket. Fig. 4 is an elevation of the receptacle without cover or gasket. Fig. 5 is a vertical section showing a modification. Fig. 6 is a section showing another modification.

The neck of a bottle or jar is shown at 1, which neck is in this case provided with a circular rib or flange 2, whose upper surface forms a seat 3 for the packing 4. This pack-

ing is preferably a gasket or ring and in any event is made of some material or composition which softens with heat, hardens in cooling, is adhesive to metal when soft, and remains in adhesion when hard. Composition packings of this general character are well known in the art, and a suitable one is described in the patent of E. Goltstein, No. 664,998, granted January 1, 1901. Above the seat for the packing rises the rim 5 of the receptacle. Adjacent to the seat 3 the neck of the receptacle is formed so as to make a surface capable of being positively engaged by the packing. I have shown two forms of the neck at this point as illustrative of many which might be used. In Figs. 1, 2, and 4 a circumferential groove 6 is formed in the neck immediately adjacent to the seat 3. In Fig. 5 the neck has a plurality of grooves at the same point, forming alternating grooves and ribs. In Fig. 6 instead of a groove is shown an inward flare or undercut. In other forms and for the same purpose the neck may be ribbed, roughened, serrated, or corrugated.

The cover 7 is of such shape as to fit and close the receptacle. In the present case it has a sunken panel surrounded by a raised bead, a flat seat 8, and a rim or flange 9. The seat 8 overlies the seat 3, and the rim 9 surrounds the rib 2, as shown. The packing is intermediate between the two seats and, as before explained, is usually a composition gasket, and it is desirable to confine the gasket as much as possible, excepting where it is desired that it shall expand. Before the cover is applied this gasket can be associated with either the cover or the receptacle. It can be laid upon the seat 3 of the receptacle, or it can, as shown in Fig. 3, have been previously applied to the cover so as to form a part of the same. The latter way is preferable, as it facilitates handling and simplifies the sealing. In either case the cover is applied to the receptacle in the presence of heat, which softens the gasket. Then as the cover is pressed into place the softened composition is forced into the grooved, ribbed, corrugated, or otherwise specially-formed surface adjacent to the seat 3, forming a locking engagement with the

jar at the same time that it is caused to adhere strongly to the preferably metallic cover. The gasket thus performs not only its natural function of making an air-tight joint, but also 5 the special function of locking the cover in place by its adhesion to the cover and by its engagement with the specially-formed adjacent surface of the receptacle. When covers are held by external atmospheric pressure due 10 to a vacuum or rarefaction in the receptacle, the locking effect described is of course additional to such atmospheric pressure; but in other cases the gasket can be used as the sole locking device.

15 In describing the operation of sealing it will be assumed for the sake of simplicity that the gasket is already inserted in the cover, as shown in Fig. 3, which is the preferred arrangement.

20 The sealing can be done in several ways. If it is desired to process and sterilize the product while in the receptacle, the cover is set in place and secured with a spring-clamp 11, as shown in Fig. 1. The receptacle is then 25 immersed in water or placed in a steam-retort and processed in the usual way. As the composition gasket softens with heat the pressure of the clamp forces it to spread and fill the groove 6 or other equivalent specially- 30 formed adjacent surface and to take the position or form shown in Fig. 2. With cooling the gasket hardens sufficiently to form a secure locking engagement with the groove, making a tight secure joint. Substantially 35 the same result can be obtained by pouring the contents into the receptacle boiling hot and then clamping the cover in place, the heat being sufficient to soften the gasket and permit the clamp to compress it. For some 40 purposes this method is preferable. If it be desired to pack the product cold, the cover is heated at the same time that it is pressed into place by any simple means.

In packing goods in a vacuum my closure 45 can be used in conjunction with the usual atmospheric-pressure seal by using a vacuum-machine in which a pressure-head is arranged in the receiver in which the jars are exhaust-

ed, means being provided for heating said pressure-head. After the creation of a vacuum within the receiver the heated pressure-head is brought to bear on the cover so as to soften the gasket and at the same time press and hold the cover in place prior to and during the readmission of air to the receiver. 50

The gasket which I employ is made of a composition which, while of a solid nature when cold, is sufficiently yielding so that the cover can be easily pried off after being punctured to destroy the vacuum by any suitable 60 instrument. If a non-yielding cement were used, it would be difficult to remove the cover without injury to the receptacle. Of course the flange 9 of the cover, as well as the receptacle, can be grooved or otherwise specially 65 formed, so as to enable the gasket when compressed to expand into and engage with the cover in the same manner that it does with the receptacle. This, however, is superfluous when the cover is made of a material to which 70 the gasket is strongly adhesive and is only desirable in case the cover is formed of such a material as glass, to which the adhesion of the composition is comparatively slight.

Having thus described my invention, what 75 I claim as new, and desire to secure by Letters Patent, is—

1. A receptacle formed with a packing-seat, and having a peripheral groove adjacent to said seat, a cover having a packing-seat, and 80 a composition gasket compressed between said seats and into said groove.

2. The combination with a receptacle, a cover for the same, and an intermediate composition packing having the described characteristics, space being provided adjacent to the packing whereby said packing when softened and exposed to pressure can expand into such space, but is otherwise confined. 85

In testimony whereof I have affixed my signature, in presence of two witnesses, this 26th day of March, 1904.

WILLIAM C. BUHLES.
